His Attorney.

UNITED STATES PATENT OFFICE

1,942,074

TIME SWITCH

George R. Townsend, Schenectady, N. Y., assignor to General Electric Company, a corporation of New York

Application October 15, 1929. Serial No. 399,835

4 Claims. (Cl. 200—38)

My invention relates to control devices and has for one of its objects the provision of a time control switch whereby different circuits may be opened and closed at predetermined intervals of time.

Another object of my invention is the provision of a switch which may be continuously driven by means of a synchronous motor. Another object of my invention is to provide a switch in which 10 adjustments may be made so that circuits may be opened and closed at any predetermined time.

A further object of my invention is to provide 15 a switch by which a snap action of a contactor thereof takes place in opening and closing the circuit.

It is a further object of my invention to produce a device as set forth above which is simple in construction and positive in operation. Other objects will appear hereinafter.

20 Although my invention is susceptible of use for other purposes, in the present case it is used to change the control of a heat supply apparatus, namely an oil burner, from one thermostat to another. The thermostats are set for different temperatures, one for controlling the oil 25 burner apparatus during the night and another for controlling the oil burner apparatus during the day.

In the preferred embodiment of my invention 30 a synchronous motor which is continuously operated from an A. C. power line is used to drive the time switch mechanism. This motor drives a shaft upon which are rotatably mounted adjustable cams. These cams cooperate with U-shaped pivoted members which carry contacts 35 thereon to open and close circuits particularly to transfer the control of the circuit from one thermostat to another.

My invention will be better understood from 40 the following description when considered in connection with the accompanying drawing and its scope will be pointed out in the appended claims.

The drawing represents a schematic diagram 45 of my invention.

A synchronous motor 10 is connected to the A. C. line L_1 and L_2 and continuously actuated thereby. A shaft 11 is driven through a series of gears from the synchronous motor 10. The gear 50 10' is rotatably mounted on the shaft 11 and frictionally drives the shaft 11 through a slip drive connection. The purpose of such a drive is to permit adjustment of the disc 12 which is rigidly mounted on the shaft 11. Such adjustment 55 would be desirable for example, when the device

is first installed or when a voltage failure for a period of time leaves the disc at an incorrect setting. On the disc 12 appear numerals indicating the time of the day and night. Rotatably mounted upon the shaft are cams 13 and 14 provided with arms 15 and 16. Spring urged pivoted members 17 and 18 connect the arms with the disc 12. The cams therefore, are made to rotate by means of the disc 12. These members are rotated in a counter-clockwise direction. The U-shaped members 19 and 20 are concentrically mounted upon a common pivot. They are provided with parts 21 and 22 which coact with the cams 13 and 14 to produce an action which is to be described later.

Rigidly attached to the U-shaped member 19 is an insulating arm 23 which carries the contacts 24 and 25. Rigidly attached to the member 20 is the insulating arm 26 which carries a second arm 27 which has contact elements upon both sides of the arm at its end. As shown upon the drawing these last contacts move between the contacts 24 and 25 carried by the arm 23. Conductor 32 connects to the arm 27 which carries contacts and one side of the circuit to be controlled by the thermostats. Conductor 33 is connected to the thermostat 31 and the contact 24 carried upon the arm 23. The thermostat 30 is connected to the contact 25 on the arms of 23 by means of the conductor 34. It will thus be seen that if the contact 24 is closed by means of the contact carried on 27 that the thermostat 31 which is the night thermostat controls the circuit. As shown upon the drawing the contact 25 is closed thus placing the thermostat 30 in the control circuit which happens to be the day thermostat. The conductors 35 and 36 go to the other side of the circuit to be controlled by the thermostats 31 and 30. This circuit referred to is the circuit going to the oil burner apparatus. The opening and closing of the thermostats controls the oil burner apparatus to furnish heat when needed and stops the apparatus when no more heat is necessary.

In operation the synchronous motor 10 continuously drives the shaft 11 and the indicating disc 12 to which the cams 13 and 14 are adjustably mounted. The shaft and cams mounted thereon are rotated in a counter-clockwise direction. The contact at 25 is closed and when in this position the part 21 of the U-shaped member 19 is slightly spaced from the cam 13. In this position the thermostat 30 is in the control circuit. As the cam 14 rotates in a counter-clockwise direction, part 22 of the U-shaped member 20 will

ride off the cam surface which will permit the U-shaped member 20 to be rotated in a clockwise direction with a snap action to close the upper contact 24 carried on the arm 23 and open the contact 25. This will permit the part 21 of the U-shaped member 19 to come into contact with the cam surface 13. Contact 24 then acts as a stop for the pivoted member 20. In this position thermostat 31 is in the control circuit. When the part at 21 of the U-shaped member 19 reaches the limit of the surface of the cam 13, this member will be permitted to be rotated in a clockwise direction with a snap action which will cause the lower contact 25 to close upon the lower contact 27, thus again placing thermostat 30 in the control circuit. A stop 22' is provided to limit the clockwise rotation of the U-shaped member 20. This stop permits the member 20 to close upon the contact 24 while element 21 is in contact with the surface of cam 13, but prevents further rotation when 21 rides off the cam 13 and closes the lower contact 25. Further rotation of the cams will again bring the cam surface 14 into contact with the part at 22 of the U-shaped member 20. Since the arm 27 is in contact with 25, both members will be caused to move in a downward direction thus keeping the contact 25 closed. Upon continued rotation the cycle will be repeated, that is, the contact carried on the arm 27 will be permitted to move in a clockwise direction, thus again closing the upper contact 24. The lower contact 25 upon the arm 23 will thus again be permitted to rotate in a clockwise direction, thus closing the bottom contact. Later both contacts will be rotated in a counter-clockwise direction. Thus, either the thermostat 31 or 30 will be placed in the controlling circuit.

By releasing the spring pressed members 17 or 18 the cams 13 or 14 may be adjusted so that they actuate the U-shaped members 20 or 19 at different times. This is accomplished by rotating the cams 13 or 14 upon the shaft 11 and then reengaging the elements 17 or 18 with the disc 12 at the proper indication.

The numerals on the darkened portion of the indicating disk indicate the hours of the night and adjusting the element 17 to any of these numerals changes the position of the cam 14 so that the pivoted member 20 coating therewith will be permitted to close the contact 24 at the designated time to place the thermostat 31 in the control circuit. A like adjustment of the member 18 will determine the operation of the pivoted member 19 to close the contact 25 at the hour of the day desired to place the thermostat 30 in the control circuit.

The embodiment of the invention illustrated and described herein has been selected for the purpose of clearly setting forth the principles involved. It will be apparent, however, that the invention is susceptible of being modified to meet the different conditions encountered in its use

and I therefore aim to cover by the appended claims all modifications in the true spirit and the scope of my invention.

What I claim as new and desire to secure by Letters Patent of the United States is:

1. A time switch comprising a shaft, means for driving said shaft, an indicating disc rigidly mounted on said shaft provided with a plurality of teeth upon its circumference, a plurality of cams rotatably mounted on said shaft and provided with arms engaging the teeth on said disc, said tooth engaging arms being adjustable with respect to said teeth to permit different settings of said cams to predetermine the operation of said switch, and pivoted U-shaped members, spring urged and concentrically mounted engaging with said cams and provided with contacts, said members being actuated by said cams to open and close said contacts. 80

2. A circuit controlling device comprising a pair of cooperating movable contact members, one biased to engage the other and the other biased to disengage the one, a pair of cams associated with said members for successively releasing the members for movement in accordance with their bias to control the circuit, and a stop disposed to be engaged by the member first released upon the release of the second member to effect relative movement of the members to control the circuit. 95

3. A circuit controlling device comprising a pair of cooperating movable switch members, two pairs of cooperating contacts, one of each pair of contacts being mounted on one of the switch members and the other of each pair of contacts being mounted on the other of the members, means for biasing one of the switch members to engage the first pair of contacts and to disengage the second pair of contacts, means for biasing the other switch member to disengage the first pair of contacts and engage the second pair of contacts, a pair of cams associated with said members for successively releasing the switch members for movement in accordance with their bias, and a stop disposed to be engaged by the member first released upon the release of the other member to reverse the engagement of the contacts. 100

4. A circuit controlling device comprising a pair of cooperating movable contact members, the first contact being biased to engage the second and the second contact being biased to disengage the first, a cam for moving the said second contact against its bias to engage said first contact and thereafter releasing the said second contact, a second cam for holding the said first contact upon the release of said second contact to effect the disengagement of said contacts, and a stop for holding said second contact upon the release of said first contact to effect the reengagement of said contacts. 120

GEORGE R. TOWNSEND.
